ANDERS E. WALLMAN AND CLIFTON D. GOFF, OF FLUSHING, NEW YORK

STREAMLINE BOAT OR PONTOON

Application filed August 2, 1928. Serial No. 297,034.

This invention relates to high speed streamline hulls for motor boats, air propelled boats and pontoons for seaplanes and the like.

5 The main object of our invention is to have a hull or float body which tends to plane over the water rather than plow through the same, and whose upper structure is formed according to certain low air resistance and streamline principles, so that a minimum resistance is encountered by the hull both in moving through the air as well as over the water.

Another object is to produce such a novel hull or float whose structure is adapted particularly for contact with the water from the water line downward, and more lightly constructed a distance above the water line to merely cleave the air and thus add very little to the weight and draft of the said hull or float.

It is also an object of our invention to so construct the hull of the character indicated, that the rear or stern thereof acts as a stabilizing means which causes the hull to automatically bank on curves in a manner quite in contrast with the action of ordinary boats and ships.

A further object is to provide a hull or float body which is adapted, not only for use as a motor boat body, but also as a float or pontoon on a seaplane or aquaplane with but slight and immaterial modifications.

Further objects and the various advantages of our invention will appear hereinafter as the specification proceeds.

In the accompanying drawings:

Fig. 1 is a top or plan view of a boat or pontoon hull made according to our invention and embodying the novel and advantageous features thereof.

Fig. 2 is a longitudinal section of Fig. 1 on line 2—2, showing the more rugged structure of the lower part of the hull while revealing the lighter construction of the upper or canopy portion, an outboard motor being also indicated by dotted lines, as also is the case in the first view.

Fig. 3 is an outline pattern of Fig. 1 on the cross section line 3.

Fig. 4 is a similar outline pattern on line 4.

Fig. 5 is another pattern on line 5.

Fig. 6 is also a pattern on line 6, ignoring the cockpit of the hull.

Fig. 7 is a further pattern on line 7.

Fig. 8 is the final pattern on line 8, the rear propeller channel being merely indicated by dotted lines.

Fig. 9 is a view of the same invention in the form of a pontoon for a seaplane, a support of which is shown in fragmentary form.

Throughout the views, the same reference numerals indicate the same parts.

In the practice of modern boat building, a new departure from the old theory of cleaving the water by the pointed and cleaver form of the prow of a boat hull, is found in the flat and stepped bottoms of the planes or floats used on seaplanes and the like. Moreover, the advantage such departures present over the old practice is immediately apparent when an aquaplane moves rapidly, for the flat planes rise to the surface of the water and skim over the same, reducing friction and energy expended to a minimum and allowing a great increase in speed over ordinary boats, but, such planes are usually made into outriggers or support means for raised hulls or fuselage bodies which are spaced a distance above their level.

In contrast with such practice, we now propose to directly form the bottom 10 of a hull 11 according to the water planing form of the lower face of a plane as found on an aquaplane or watersled but lengthening the same to depart in a measure therefrom and somewhat approach the construction of a flat bottomed boat having no keel whatever. However, in order to assist in providing a steady-ing effect, the two sides 12 and 13 of the bottom 10 may be slightly peaked downward to form a ridge 14.

A great departure of the present invention from common practice is also introduced by practically reversing the whole boat and turning the blunt rear to the front and the wedge shaped prow to the rear.

In addition, the new front end or prow is brought up in a curve at 15 to give the planing bottom a tendency to climb up on the sur-

face of the water, the skimming effect being much increased by a step or shoulder 16 formed in the bottom.

Then, the edges all around the hull at 17 5 and 18 may be somewhat slightly rounded if desired, in order to reduce friction up to the shoulder 16, the edges beyond the latter being preferably more sharp at 19 and 20. At the rear of the bottom 41, on the other hand, 10 the bottom is again preferably brought up above the water line in a curve at 21, although this is optional, the water tending to rise slightly and produce a very thin wake thereby. The plan of the bottom follows the general outline of the whole boat which is 15 reversed from the conventional types, as already mentioned and the form of which may now be more minutely examined.

The nose 22 of the hull is made somewhat 20 dull, as its office is not to cleave water, but to ride over it, and the hull is rapidly widened behind it at 3 and then gently curved toward the midship section at 4, 5 and 6, after which the curvature is only gradually increased to 25 form a streamline convergence of the sides 23 and 24 beyond 7 and 8 to the elongated rear end 25. By using such a form, the hull not only has the advantage of the form of a plane, but also that of a boat of very shallow draft.

30 However, the main feature of the stern bottom 41 is that it is inclined downwardly toward the rear so that the extreme portion of stern 25 practically sags down on the water, except that at that point the bottom is 35 brought upward in the curved end 21, this rear section as a whole provides a secondary rear sledding section of the hull bottom in addition to the main forward portion of the bottom 10 back to the shoulder 16. This provides two highly advantageous results. The first has already been indicated, namely, that a relatively light and flat wake is produced by the boat when proceeding over the water, due to the fact that the inclined stern bottom 41 40 of stern 25 rides upon the water in such an effective sledding position as to receive very considerable support from the water, thus flattening the wake. The second advantage is in great measure derived from the first and 45 resides in the fact that boat is automatically self banking when turning on a curve in the water, and can be run around a rather sharp curve at the highest speed without taking any precaution whatever, the banking action taking place as in the case of an aeroplane passing around a curve in the air. The hull can thus be considered as having an integral rear stabilizer in its stern 25, and when the hull has a motor channel 31 as will be further explained in this case, the hull may be 50 considered as equipped with a pair of such stabilizers due to the divided condition of the stern.

Furthermore, the upper portion or canopy 65 of the hull from above the water line indi-

cated at 26 is made rather blunt at the nose, rising very rapidly in a sharp curve toward section 3, the curvature being gently straightened before reaching the same and from that point practically to section 5, the form of the canopy is at the top substantially horizontal. The hull may have a cockpit, generally indicated at 27 and provided with a cowl 28 and a rear board 29 upon which an outboard motor may be mounted, as indicated at 30.

70 From the cowl 28 back to the very extreme end of the rear 25 over the water line, the hull canopy curves gently down in order to co-operate with the elongated form of the hull to break any tendency to form a vacuum behind the boat, then, again, the relatively blunt nose at the prow is formed to abruptly part the air in front and cause the air pressure to hold down the nose and thereby hold the hull on an even keel when it tends to rise through planing action while gaining speed over the water.

75 The rear of the hull has a propeller channel 31 cut into the same and provided with the side walls 42 and 43, in order to provide draft space for the motor 34 and its propeller, and is preferably covered by a plate 32 to conform with the general plan of the hull, the board 9 supporting the motor, the plate 32 being, however, optional. Naturally, when the edges or side of the hull at their junctions with the top of the canopy are rounded to reduce friction they are gradually merged with the top to form a smooth unit of streamline form and proportions. The introduction of the cowl serves in this form to sweep the air in a curve over the cockpit and protects an operator in the cockpit from the wind produced by speedy running.

80 The lower hull proper consists principally of the outer heavy layer of wood 35 or other suitable material, reinforced by heavy ribs as at 37. The canopy proper may be a canvas sheet, laminated wood or sheet metal 33, which is supported by light ribs as indicated 85 at 36, the board 38 forming the dividing line between the hull and the canopy and serving as an anchorage for the ribs of both.

85 Of course, the board 38 and the ribs may be 90 displaced by other structure, according to desire, the main principles of the hull not being altered thereby, though the canopy is preferably made much lighter than the bottom as already explained.

95 In the last view, the cowl, cockpit and rear channel are omitted from the pontoon or float 39, and instead a supporting strut 40 of a seaplane (not shown) is partially illustrated. The principles of the pontoon are substantially the same as before in the case of the boat hull, and will provide support upon the water while offering a minimum of resistance to the latter and to the air when a seaplane thus equipped is set in motion per-

mitting the latter to attain a high speed very quickly.

The upper portion 48 of the pontoon 39 corresponds with the canopy 34 of the hull, the prow 44 with the hull prow 34, also the shoulder or step 45 with the bottom shoulder 16 of the hull before described in detail. The stern 47 here of course corresponds with stern 25 of the hull, and the rear sledding section inclined downwardly from shoulder 45 corresponds with the similar structure 21 and 41 of the hull.

The term water line as herein used must not be too strictly construed as meaning at all times the actual water line but is intended to denote a point upon the hull which is never below the actual water line but always at least upon its level or safely above the same.

Variations may be resorted to within the scope of our invention.

Having now fully described our invention, we claim:—

1. A speed boat including a hull having a relatively obtuse prow and an elongated stern, a motor support spaced within said stern, there being a propeller channel extending to the rear extremity from said support, a rigid streamline canopy surmounting said hull in such manner as to conform to the outline thereof and cover said propeller channel, there being also a cockpit in said canopy extending down into said hull, and a wind deflecting cowl upon said canopy adjacent said cockpit.

2. In a speed boat having a hull provided with a water planing bottom including an intermediate transverse shoulder, said hull being generally streamline in plan outline, the combination with a streamline canopy rigidly secured to said hull and conforming to the outline thereof, of a downwardly inclined rear section in said hull bottom beyond said shoulder terminating in an upwardly curved extremity extending above the water line.

3. In a speed boat or pontoon, the combination with a hull having a water planing bottom, including an intermediate transverse shoulder, said hull being generally streamline in plan outline, of a downwardly inclined integral rear section upon said bottom disposed beyond said shoulder terminating in a rear extremity which is curved upward toward the water line and arranged to make contact with the water when the hull is propelled forward and the forward section of the bottom including said shoulder glides over the water.

4. In a streamline boat or pontoon, the combination with a hull having a water planing bottom which includes an intermediate transverse shoulder, said hull being generally streamline in plan outline, of a rigid rear section integral with said bottom downwardly inclined beyond said shoulder toward the

rear, said rear section terminating in a curved extremity directed upward to the water line, and a streamline canopy of relatively lighter construction than said hull surmounting the same to form a unit therewith and conforming to the generally streamline outline of said hull.

5. In a streamline boat or pontoon, the combination with a hull having a bottom provided with an intermediate transverse shoulder, of a rear section rigid with said bottom downwardly arched in gradually inclined manner toward the rear and terminating in an upwardly curved extremity extending above the water line, there being a streamline canopy of relatively lighter construction than said hull surmounting the same to form a unit therewith.

6. In a speed boat, the combination with a hull having a water planing bottom including an intermediate transverse shoulder, of a rear section rigid with said bottom downwardly inclined from said shoulder toward the rear and terminating in an upwardly curved extremity extending above the water line, and a pair of interior walls in said rear providing a propeller channel open to the rear and dividing said inclined and curved section into a pair of integral stabilizers in said hull for banking said boat on a curve.

7. In a speed boat, the combination with a hull having a water planing bottom including an intermediate transverse shoulder, of a rear section rigid with said bottom downwardly inclined toward the rear for planing upon the water, and a pair of interior walls providing a propeller channel open to the rear and dividing said inclined rear section into a pair of integral stabilizers in said hull for automatically banking said boat when going around a curve.

8. In a speed boat, the combination with a hull having a water planing bottom including an intermediate transverse shoulder, of a rear section rigid with said bottom downwardly inclined from said shoulder toward the rear and terminating in an upwardly curved extremity extending above the water line, a pair of interior walls in said rear providing a propeller channel open to the rear and dividing said inclined and curved rear section into a pair of integral stabilizers in said hull, and a streamline canopy surmounting said hull to form a unit therewith, said canopy being of relatively lighter construction than said hull.

9. In a streamline boat or pontoon, a water planing bottom which consists of a pair of consecutive rigidly arranged water sleds arranged at different angles along said boat, said water sleds being so formed and arranged that the second sled is generally arched to form a concave bottom which is inclined downwardly toward the rear and

terminates in an upwardly curved extremity directed up toward the water line, said downwardly inclined and arched sled bottom merging gradually and imperceptibly with the rear upward curve thereof.

10. A speed boat including a hull having a relatively obtuse prow and an elongated stern, there being a propeller channel opening rearwardly in said stern, means in said stern for 10 accommodating a motor whose propeller may be operated through said channel, a rigidly mounted canopy of streamline form surmounting said hull and both conforming with the outline thereof and tending to form a unit 15 therewith, there being also a cockpit extending down through said canopy into said hull, and a water sledging bottom beneath said hull.

11. A streamline boat or pontoon of both 20 vertical and plan streamline form, including a hull, there being a water planing bottom on said hull having an intermediate shoulder and conforming with the streamline plan of the hull, there being also a canopy surmounting said hull likewise conforming to the streamline outline plan of said hull, a downwardly arched section in said bottom, integral therewith and curving down toward the rear, and an upwardly curved section terminating said downwardly arched section and forming the end section of the hull whose 25 curve reaches up to the water line.

12. In a streamline boat or pontoon, the combination with a hull having a water planing bottom, including an intermediate transverse shoulder, of an integral rear section in 30 said bottom beginning at said shoulder and curving gently downward toward the rear and then curving upward toward the water 35 line.

13. A speed boat including a hull having a relatively obtuse prow and an elongated stern, said stern being bifurcated to provide a propeller channel, a canopy upon said hull conforming to the outline thereof and extending 40 rearwardly so as to cover said propeller channel, and means associated with said hull for supporting a motor, there being a water sledging bottom beneath said hull.

14. A speed boat including a hull of generally streamline form provided with a water sledging bottom including an intermediate transverse shoulder, a rear section in said hull bottom beyond said transverse shoulder which 45 is inclined downwardly toward the rear in curved manner and terminated in an upwardly curved extreme section which reaches the water line.

15. A speed boat or pontoon including a 50 hull having a relatively obtuse prow and elongated stern, a water planing bottom beneath said hull conforming to the plan outline thereof having an intermediate transverse shoulder, a section beyond said shoulder 55 which is inclined downwardly toward the

rear in slightly curved manner so as to gradually increase the downward pitch, and a rear end section in said bottom merging imperceptibly with said downwardly inclined section and curving uniformly upward toward the 60 water line.

16. A speed boat or pontoon including a hull surmounted by a streamline superstructure, a water planing bottom beneath said hull having an intermediate transverse shoulder, a section integral with said bottom beyond said shoulder gradually curved downward with increasing pitch toward the rear, and a rear extreme end portion merging with 65 said downwardly curved section so as to curve upwardly uniformly therefrom to the water line.

In testimony whereof, we have signed our names to this specification this 26 day of July, 1928.
